UNITED STATES PATENT OFFICE.

PAUL R. TAPPAN, OF MANSFIELD, OHIO.

BURNER.

1,184,892.

Specification of Letters Patent.

Patented May 30, 1916.

Application filed June 5, 1915. Serial No. 32,278.

To all whom it may concern:

Be it known that I, PAUL R. TAPPAN, a citizen of the United States of America, residing at Mansfield, in the county of Rich-
5 land and State of Ohio, have invented cer-
tain new and useful Improvements in Burn-
ers, of which the following is a specification.

This invention relates to new and useful
improvements in burners and more particu-
10 larly to a gas burner, and it has for its pri-
mary object to save gas and be efficient in
operation throughout.

One of the objects of this invention is to
provide a means of preventing the gaseous
15 mixture from "popping back" in the burner
and blowing out the flame when the flow of
gas is decreased (thereby preventing the
proper combustion thereof) which comprises
20 the use of a member which obstructs the
passageway of the gaseous mixture, said
member preferably consisting of a sheet of
foraminous material used in combination
25 with means for enlarging the area of the
passageway of the mixture at the point of
the insertion in the passageway of the for-
aminous material; said material compensat-
30 ing and allowing for the space of the pas-
sageway taken up by the walls forming the
openings in the mesh of the gauze, screen
or other foraminous plate or material.

A further object is to thoroughly atomize
the mixture to provide for proper combus-
tion.

Other objects will be set forth hereinafter
35 and those features of construction, arrange-
ments and combinations of parts to be pro-
tected will be defined in a succinct manner
in the annexed claims.

For a full understanding of the invention,
40 reference is had to the following specifica-
tion, and the accompanying drawing where-
in like characters of reference designate cor-
responding parts, and Figure 1 is a frag-
mentary top plan of the top of a stove em-
45 bodying the present invention in its pre-
ferred form; Fig. 2 illustrates the same in
side elevation with part in section showing
the insertion of sheet of foraminous mate-
50 rial between the elbow burner which is
formed of two parts; and Fig. 3 is a plan
view of the elbow burner showing the for-
aminous material and air and gas mixing
pipe applied thereto.

Referring more particularly to the draw-
55 ing, numeral 1 designates the top of the

stove, 8 the gas and air supply pipe and 3
a disk having radial arms 4 projecting there-
from and resting upon the stove top at the
edge of the stove opening 5.

Reference numeral 6 represents the gas 60
controlling valve adapted for regulating the
supply from the pipe 2' to a conventional
type of air mixer 7 which is carried on the
outer end of air and gas supply pipe 8.

Threaded on the inner end of the pipe 8 is 65
the gas burner 9 which is of elbow shape
and has an upwardly directed tip 10 dis-
posed immediately below the disk 3 so that
the apex 12 of the inner cone 13 of the flame
issuing from the single, large opening 11, 70
which is formed in jet or tip 10, will reach
or touch the bottom or under side of the disk
without leaving any air space between the
flame and disk.

The elbow burner 9 is composed of two 75
parts and a sheet of foraminous material 9'
is interposed therebetween and is preferably
held in place by the bolts 9² which pass
through the ears 9³. The area 9⁴ of the
elbow is gradually enlarged from the end 9⁵ 80
of the pipe 8 to compensate for the space
taken up by the walls forming the opening
in the foraminous material. When the gase-
ous mixture passes through the foraminous
85 material, it is thoroughly atomized.

In this connection it will be noted that
the burner is much easier to clean than the
common type of burner because the latter
has a plurality of small apertures whereas
one large opening 11 is provided in the body 90
9. Furthermore, in a burner of this type,
it is well known that the apex of the inner
cone of the flame is the hottest part thereof,
and hotter than the outer flame part repre-
sented by arrows 14, which surrounds cone 95
13. Therefore, the disk 3 is in direct contact
with the hottest part of the flame.

The disk retains the heat radiation of the
flame cone 13 in close contact with a super-
posed vessel and also performs the function 100
of a guard in preventing foreign matter
from entering the burner opening 11 as when
the cooking vessel or utensil boils over.
The outer part of the flame of the burner
spreads over the entire bottom of the vessel 105
thereby placing the same in a hotter zone
than if air was allowed between the flame
and the bottom of the vessel such as when
the flame does not touch the latter. The
disk further serves as a baffle to the flame to 110

prevent the latter leaping and burning a person while removing a vessel.

The burner is very simple in construction and manufacture, consisting of a piece of 5 pipe, or its equivalent, having one end bent at right angles and made in two parts. It is very economical, cheap, easy to remove and replace, and has been tested as to its increased efficiency and gas saving.

10 The loss of heat resulting when using a gas stove equipped with the ordinary burners is due to imperfect combustion and the vessel not being in contact with the flame. Both of these undesirable conditions are effectually overcome by the present device 15 which results in a saving of gas and a very pronounced increase in efficiency.

What is claimed is:

1. A burner including a hollow body 20 formed with an inlet and an outlet, the sectional dimensions of the interior of the burner being gradually increased from the inlet and outlet toward the central portion of the burner, and a plate of foraminous material secured within the burner at the point 25 of maximum interior dimensions, said plate

being inclined with respect to the plane of both the inlet and outlet.

2. A burner constructed in two parts, having an inlet and an outlet arranged at 30 an angle to each other, and a foraminous plate arranged within the burner and at an angle to the inlet and outlet and midway therebetween.

3. A burner including approximately du- 35 plicate sections, each having a fuel opening at one end, and a larger opening at the op- 40 posite end, the edge of the section at the end including the larger opening being arranged at an angle to the edge of the section includ- 45 ing the fuel opening, means for securing the sections with the edges of the ends including the larger openings in adjacent relation, and a foraminous plate held between such edges.

In testimony whereof I affix my signature in presence of two witnesses.

PAUL R. TAPPAN.
